C. N. CARLSON

STORM SASH FASTENER

Filed Oct. 28, 1926

Inventor

CHAS' N. CARLSON

Chas' N. Carlson

Attorney

UNITED STATES PATENT OFFICE.

CHARLES N. CARLSON, OF VIRGINIA, MINNESOTA.

STORM-SASH FASTENER.

Application filed October 28, 1926. Serial No. 144,782.

This invention relates to storm sash fasteners and relates particularly to that type of fastener which operates simultaneously with the movement of the lower sash of the window to which the storm sash is applied.

The principal object of my present invention resides in the provision of means operable in conjunction with the fastener for more positively holding the storm sash tightly against the abutments of the window frame when closed.

Another object is to provide simple means for limiting the upward movement of the sash of the window by which the storm sash fastener is operated.

Other objects and advantages of the invention will appear in the further description thereof.

Referring now to the accompanying drawing, forming part of this application, and wherein like reference characters indicate like parts:

Figure 1 is a perspective view of a fragmental portion of a storm sash and window frame illustrating their open cooperative relation resulting from the attachment of my improved fastener; and

Figure 2 is a broken side elevation of the window frame and storm sash in its closed position.

1 represents the inner face of one side of a common window frame provided with the common inner and outer stops 2 and 3 respectively, and, in dotted lines, as at 4, is represented the lower sash of the window as mounted within the frame 1 and susceptible of vertical adjustment as is common.

5 represents the lower fragmental portion of a common storm sash, and 6 is the fastener arm which is pivotally connected as at 7 to the bracket 8 upon one edge of the storm sash, and at its opposite end as at 9 to the bracket 10 which is securely fixed as by suitable screws or the like to the sash 4;

45 the fastener arm here illustrated is preferably of the design shown in my former Patent No. 1,607,944 differing however in that at the window sash end it is provided with a depending stop member 11, secured as by 50 suitable rivets indicated at 12 adjacent the pivotal point of said arm, the stop member 11 having a squared end flush with the end

of the arm 6, so that when the window sash 4 is raised to a position which will bring the arm 6 substantially parallel with the squared end of the stop 11 it will abut against the face of the bracket 10 and thus stop the upward movement of the sash, assuring against disarrangement of the auxiliary attachment to the fastener hereinafter described, as well as insuring the proper relation between the window sash and the storm sash at all times.

The auxiliary attachment connected with the fastener arm consists of the flexible cord, 65 rope, or wire, as the case may be, indicated at 13, which is provided with a suitable eye 14 at either end thereof, said eyes being designed to encircle the pivotal support at either end intermediate of the arm and 70 brackets to which the latter are attached, the wire being payed through the screw eye 15 fastened within the stop 2 spaced somewhat above the uppermost travel of the window sash 4 as limited by the stop heretofore 75 described upon the innermost end of the fastener arm. This wire is of the proper length to permit of functioning as disclosed in the drawings, and holding the storm sash tightly 80 against the stop 3 when the window sash is in closed position, thus providing a direct pull on the wire intermediate of the screw eye 15 and the pivotal point 7. As is obvious the stress upon the wire when the window is closed may be governed by the length 85 thereof as well as by the position of the eye 15, and the eye may be of somewhat different construction and provided with a roller if desired, as its specific shape does not form part of my present invention other than that 90 the hole therein must be sufficiently large to permit of either eye 14 freely passing therethrough to allow the same to be readily installed.

Having thus described my invention, what 95 I claim and desire to secure by Letters Patent, is:

1. The combination with a storm sash fastener attached at one end to a storm sash and at the opposite end to a window sash, 100 of a limiting stop attached to said fastener, flexible means attached at one end to the storm sash and at the other end to the window sash, and fixed means through which the

flexible means is payed so positioned as to prevent damaging engagement of the fastener arm therewith.

2. In combination, a storm sash fastener attached at one end to a storm sash and at the opposite end to a window sash, a flexible cord having its ends attached to the ends of

the fastener, and fixed means on the window frame adjacent the window sash through which the cord is payed for the purpose described.

In testimony whereof I affix my signature.

CHARLES N. CARLSON.
